UNITED STATES PATENT OFFICE.

WALTER L. MAJORS, OF ST. LOUIS, MISSOURI, ASSIGNOR TO MAJORS OXFORD COLLEGE, OF ST. LOUIS, MISSOURI, A CORPORATION OF MISSOURI.

MACHINE FOR THE TREATMENT OF THE SCALP AND HAIR.

Application filed June 24, 1921. Serial No. 480,255.

To all whom it may concern:

Be it known that I, WALTER L. MAJORS, a citizen of the United States, residing at the city of St. Louis, in the State of Missouri, have invented certain new and useful Improvements in Machines for the Treatment of the Scalp and Hair, of which the following is a specification.

This invention has for its object the use 10 of air, preferably compressed air, for treating the scalp and hair, including the removal of dandruff, dirt, loose hairs, or the clippings of hairs from hair-cutting.

Prior to this invention the drying of hair 15 by means of a blast of cold air has been known but this is the only method that contemplates and the only apparatus adapted to dry hair on the scalp by a hot moist blast of air, and this apparatus is adapted to deliver a blast of either hot or cold moist air, which is regarded as a very desirable 20 method of treating the hair, because merely dry air causes hair to become brittle and break.

25 This invention combines in one compact machine means for various purposes for which air-suction may conveniently be used in a barber shop or hair-dressing parlor.

In the accompanying drawings forming 30 part of this specification, in which like numbers of reference denote like parts wherever they occur,

Figure 1 is a side elevational view of this machine,

35 Figure 2 is a sectional view on the line 2—2 in Figure 1; and

Figure 3 is a vertical sectional view on the line 3—3 in Figure 1.

A weighty base 1 rests upon floor 2. A 40 standard 3 rises from base 1 to a convenient height, where it receives inverted cup 4 for the support of the main parts of the apparatus.

An air-suction pipe or tube 5 leads from 45 clippers 6, which may be kept at any convenient location and not upon the floor 2. A pipe leads below the level or waterline 8 of the liquid 9 in the jar or receptacle 10, having at its top screwthreads 11 adapted to receive and co-operate with the screwthreads in the interior of the flange on cap 12. The air-suction induced, as hereinafter described, by fan 13 draws the fine particles of hair and dirt and dandruff from the scalp, and, also, 50 some longer hairs from clippers 6 when in

use on the head through tube or pipe 5 and into pipe 7, and follows the direction indicated by the arrows within pipe 7, and emerges from the liquid 9 into the upper part of the space within jar 10. Any dandruff, dirt, or hair particles thus passed into the liquid 9 from pipe 7 becomes wet and, thereby, weighted, and is thus removed from the air-current that follows the direction of the arrows shown to the right within receptacle 10, and emerges through an opening into chamber 14 and thence into pipe 15.

Fan 13 is located within casing 16 and draws air through pipe 17 having inlet ports 18. Pipe 17 connects by means of joints or elbows 19 and pipe 20 with pipe 15, which at its lower end is fastened by union 21 to chamber 14, which is the exit from the interior of receptacle 10. An electrical heater 22 is located in pipe 17, and when the switch 23 is turned on heats the air that passes through pipe 17 and the fan 13, so that when the said air passes through pipe 24 and is emitted at 25 adjacent the head of the person being treated the air is warm 80 and is also moist, on account of having been drawn through the liquids 9. By this arrangement, the heater 22 is air cooled.

As the air passes through pipe 24 toward the exit 25 it strikes the blades of a rotary motor 26 and rapidly rotates the same in its casing 27, which results in the rotation of shaft 28 and the consequent rotation of flexible shaft 29. Shaft 29 is connected to shaft 30 and thereby rotates a tool such as a manicure buffer 31.

An electric motor 32 is inclosed in casing 33. The said motor 32 drives fan 13 and, thereby, exerts the air-suction and pressure hereinbefore described. Wire 34 leads to 95 motor 32 and branch-wire 35 to lamp 36. Motor 32 and lamp 36 are turned on by switch 37.

The current for heater 22 passes through wire 38 and is turned on by switch 23 and simultaneously lights lamp 39 for display or illuminating purposes. Switch 23 can not be turned on to generate heat in heater 22 until the motor 32 has been turned on by switch 37, which fact is to be determined by 100 the fact that lamp 36 is burning. If heat were turned into heater 22 without this safeguard the heater 22 would burn out.

Jar 40 contains liquid disinfectant material 41, which imparts a pleasing odor to 110

the air emitted at exit 25 and, furthermore, is taken into the air-current of warm air that passes through tube or pipe 17 and fan 13 and pipe 24, and thence out from its 5 exit 25.

Jar 40 is provided with base-plate 42 and screw-cap 43. Long bolts 44 and nuts 45 attach jar 40 to the upper wall of motor-casing 33.

10 The inlets 18 of pipe 46 allow suction of warm or hot air impregnated with the disinfectant 41 into the current of air drawn by fan 13. Additional air is inhaled through funnel 47 and openings 48.

15 Bolts 44 are provided with heads 49, by means of which cap 43 as well as base-plate 42 is secured to jar 40. A casing 50 within jar 40 at the base-plate 42 extends through the neck 51 of jar 40, which neck is closed 20 by collar 52 and gasket 53. The upper end of casing 50 extends without jar 40 and receives cap 43, which is fastened thereto by heads 49 of bolts 44. A U-loop 54 connects bolts 44 at one end.

25 Spreader 55 within jar 10 is fastened by collar 56 and set-screw 57 to the outside of pipe 7 and atomizes under the pressure of air entering jar 10 through pipe 7 the water 30 or other liquid 9 within jar 10, and prevents the suction of all of the liquid out of jar 10 through pipe 15, and by reason of the said 35 atomization only the moisture, so to speak, from liquid 9 is drawn through the pipe 15 and carried through pipe 17, fan 13, pipe 24, and exit 25. The screen 58 located in pipe 24 prevents the emission of anything at exit 25 in the way of particles of hair or dirt that may have escaped through the liquid 9 in receptacle 10.

40 Having thus described this invention, I hereby reserve the benefit of all changes in form, arrangement, order, or use of parts, as it is evident that many minor changes may be made therein without departing from 45 the spirit of this invention or the scope of the following claims.

I claim:

50 1. The herein described method of treating the scalp and hair consisting of applying air-suction thereto, passing the same air into a container and through a liquid within the said container, atomizing the said liquid, drawing the said air particles of the said liquid through a conduit, and forcing the 55 same by fan-pressure into contact with the patient's hair.

60 2. The herein described method of treating the scalp and hair consisting of applying air-suction thereto, passing the same air into a container and through a liquid within the said container, atomizing the said liquid, drawing the said air particles of the said liquid through a conduit, and forcing the 65 same by fan-pressure into contact with the patient's hair, and there being a heater in-

terposed in the course of travel of the said air with its accompanying moisture, whereby the said moist air is applied in a heated condition to the scalp and hair of the patient.

3. The herein described method of treating the scalp and hair consisting of applying air-suction thereto, passing the same air into a container and through a liquid within the said container, atomizing the said liquid, drawing the said air particles of the said liquid through a conduit, and forcing the same by fan-pressure into contact with the patient's hair, there being a heater interposed in the course of travel of the said air with its accompanying moisture, whereby the said moist air is applied in a heated condition to the scalp and hair of the patient, the said heat being applied to the said air and moisture during the suction of the same.

4. An apparatus of the character described comprising a motor, a fan adapted to draw air and to force air out of a pipe leading therefrom, another pipe leading to the fan, and a liquid container interposed in the last-mentioned pipe.

5. An apparatus of the character described comprising a motor, a fan adapted to draw air and to force air out of a pipe leading therefrom, another pipe leading to the fan, a liquid container interposed in the last-mentioned pipe, the said container having within it a spreader located above the liquid level.

6. An apparatus of the character described comprising a motor, a fan adapted to draw air and to force air out of a pipe leading therefrom, another pipe leading thereto, and a liquid container interposed in the last-mentioned pipe, the continuity of the said pipe being broken within the said container.

7. An apparatus of the character described comprising a motor, a fan adapted to draw air and to force air out of a pipe leading therefrom, another pipe leading thereto, a liquid container interposed in the last-mentioned pipe, the continuity of the said pipe being broken within the said container, a branch of the said pipe extending within the said container below the waterline, there being located in the suction-line a heater, and means for controlling the said heater.

8. An apparatus of the character described comprising a motor, a fan adapted to draw air and to force air out of a pipe leading therefrom, another pipe leading thereto, a liquid container interposed in the last-mentioned pipe, the continuity of the said pipe being broken within the said container, a branch of the said pipe extending within the said container below the waterline, there being located in the suction-line a heater, and means for controlling the said heater, the said means being so located and arranged that the heater can not function prior to the starting of the fan-motor.

9. In an apparatus of the character de-

scribed, a fan, means for actuating the same, an air exit on one side of the fan and an air-suction pipe on the other side of the said fan, and a disinfectant container having an outlet connection with the said suction-pipe.

10. In an apparatus of the character described, a fan, an air conduit connected to the fan inlet, a disinfectant container, and branch pipes from the said air conduit and having communication with said container.

11. An apparatus of the character de-

scribed comprising a casing having an air inlet and an air outlet, a fan in the casing, a suction conduit connected to the air inlet, a conduit connected to the air outlet and having an air exit, a rotary motor interposed in the last-mentioned conduit, and a tool driven by said motor.

In testimony whereof I hereunto affix my signature.

WALTER L. MAJORS.
